UNITED STATES PATENT OFFICE.

GEORGE L. HEDGES, OF CLEVELAND, OHIO, ASSIGNOR TO THE P. A. GEIER COMPANY, OF CLEVELAND, OHIO, A CORPORATION OF OHIO.

CLOTHES-WRINGER MECHANISM.

Application filed October 18, 1923, Serial No. 669,264, and in Canada August 31, 1923.

My invention relates to improvements in clothes wringer mechanism and has for its object the provision of means for adjusting the pressure of the wringer rolls and for instantaneously releasing such pressure. Secondarily, my object contemplates the association with suitable pressure mechanism of extremely simple means or mechanism not liable to get out of order, which shall accomplish the results above indicated.

My improvements, as applied to a power-operated wringer mechanism embodying further features of my invention not specifically claimed herein, comprise a bowed leaf spring through which the pressure may be applied to the bearings of the upper roll, with which spring is associated a cam and its co-acting pressure member forming, in effect, a tilting pressure-transmitting appliance affording a plurality of positions for effecting variable spring pressure, ranging from zero to a maximum pressure; said tilting appliance being so designed as to effect the instantaneous release of pressure in any position of the actuating members. In the embodiment shown the cam is positioned in the mid-upper portion of the wringer frame and is rotatable approximately through 90° for shifting from one position to another; against this cam a pivoted member, forming therewith a readily releasable connection and disposed in overweighted position upon the spring, is adapted to bear against a flattened face in each of three actuating positions.

The structural features of my present invention, together with the advantages and operation thereof, may best be explained by making reference to the accompanying drawings, wherein:

Figure 1 is a view in front elevation, partially broken away and in section, illustrating a power-actuated wringer embodying this invention;

Fig. 2 is an irregular vertical section and end elevation, indicated by line 2-2, Fig. 1, Fig. 3 is a fragmentary sectional view illustrating the positions of the cam and tilting pressure-transmitting member when the latter is released and the upper roll freed from pressure, and

Fig. 4 is a similar view of these parts with the cam rotated into its position insuring minimum pressure between the rolls.

Throughout the several figures of these drawings I have employed the same charac-

ter of reference for indicating similar parts.

In the instant embodiment of my invention there is provided a hollow metallic frame *a* for the wringer; preferably cast from aluminum. The lower roll *b* is stationarily journaled intermediately of the two legs of the frame, power being applied thereto through the clutch member *c*, sectionally shown at the right.

The upper roll *d* rests upon the lower roll *b*, but it is freely movable vertically unless pressure is applied through the stiff leaf spring *e* which bridges the terminal wooden bearing members *d'*. A yoke *e'* is positioned at the bowed portion of said spring *e* and serves to pivot the overweighted member *f* thereon. This pressure member, as best shown in Fig. 1, comprises the overweighing horizontal arm *f'*, lateral pivots *f''*, an upright curved portion *f*³, a substantially rectangular bearing face *f*⁴ and lateral lugs *f*⁵.

The actuating member controlling the pressure-transmission and spring is journaled in the upper portion of the frame *a* and freely rotatable in suitable bearings. It comprises an intermediate cam member *i* substantially C-shaped in cross section and duplicated upper and lower levers *g*, *h* at each side of the frame. This cam preferably has three slightly flattened engaging faces, *i'*, *i''* and *i*³, disposed at increasing radial distances from the axis of the actuating member and substantially at 90° from one another. However, it is not essential that these flattened faces shall be provided, inasmuch as the cam normally will remain in any adjusted position, within limits, regardless of such flattened contour or its elimination.

It will be observed that opposing pairs of ribs *a'* and *a''* are provided interiorly of the frame *a* adjacent to the pressure-transmitting member and respectively in position to be engaged by the extended pivots *f''*, the coacting ribs *a'* and *a''* forming a vertical slide wherein the pivot is freely movable and thereby defining the position of the member *f*, the yoke *e'* and spring *e* in their vertical movement.

The lugs *f*⁵ form limiting stops for the toggle member *f* and its overweighing arm *f'*, as indicated in Figs. 1 and 2.

As viewed in Fig. 1, the tensioning movement of the actuating levers and cam member is in a counter-clockwise direction for engaging a cam face with the end of the pressure or toggle member *f*, while the reverse ro-

105

110

tation of said levers and cam member from any tensioning position with a cam face, serves immediately to actuate the tilting member slightly to the left beneath the cam face and thereby free the spring from all pressure and constraint. Under these circumstances the upper roll merely rests upon the lower roll with its own weight or it may be forced freely toward the upper part of the frame by any article or member entering between the wringer rolls. This insures the essential safety of the wringer mechanism by permitting instant release of the roll pressure.

15 Referring to Fig. 3, which shows a zero pressure position of the cam, it is seen that rotation thereof will place an initial tension upon the spring by reason of the engagement of cam face i' with the bearing face f^4 , as shown in Fig. 4, when rotated 90° from its zero pressure position. Similarly, the further rotation of the cam through a 90° arc will engage the face i'' with the angularly extended bearing face f^4 of the pressure-transmitting member (which position is not specifically shown in the drawings), thereby placing the intermediate tension upon the spring, or the continued rotation of the cam in counter-clockwise direction through another 90° arc will bring it to the position shown in Fig. 1, which insures a maximum tension and roll pressure.

Upon considering the relation of the pivoted or tilting member with its coacting rotatable cam positioned immediately above its pivotal mounting, but restrained from any movement toward the right by reason of the engagement of lugs f^5 with the abutments a^3 provided laterally upon the frame, it will be seen at once that the counter-clockwise movement of the cam from its zero pressure position through 270° must continue to place increasing pressure upon the spring. On the other hand, since the tilting member is free to move toward the left, any clockwise rotation of said cam will serve to break what in effect is a toggle joint action by turning the bearing face f^4 from beneath said cam, thereby causing the disengagement of the members and the instant release of the spring. The curved section f^3 of the pressure-transmitting member adapts the angular extremity of said member to enter rearwardly of the cam for assuming the position of Fig. 3, whereby pressure may be again applied. This mechanism is not necessarily limited to clothes wringers. In its particular use, however, if the clothes between the rolls become bunched, if buttons are liable to be torn off, or if the hand or fingers of the user shall accidentally be engaged between the rolls, their pressure may be instantly released, and any damage averted.

Having now described the apparatus embodying my invention and the objects and ad-

vantages attainable thereby, I claim as new and desire to secure by Letters Patent the following:

1. The combination with an element adapted to be placed under tension, of a tensioning spring operatively associated with said element, an overweighted pressure transmitting member pivotally mounted to coact with said spring, a detent for said member positioned to limit the pivotal motion of the pivoted member to position the same in pressure exerting position, and a rotatable cam acting on said pressure transmitting member and having a releasing position and a plurality of actuating positions, for relieving the pressure on said spring by the pressure transmitting member, and subjecting the spring to pressure.

2. In a wringer mechanism, the combination with a pair of opposing wringer rolls, of a tensioning spring connected to one of the rolls, a translatable overweighted pressure member pivotally mounted to coact with said spring, a detent for said member positioned to limit the motion of the pivoted member to position the same in pressure exerting position, and a rotatable cam acting on said pressure member and having a releasing position and a plurality of actuating positions for relieving the pressure on said member and thereby said spring and wringer rolls and subjecting the member and thereby the spring and rolls to varying conditions of pressure.

3. In a clothes wringer, the combination with paired wringer rolls, one roll being adjustable toward and from the other, of a spring operative upon one of said rolls, a pivoted member located adjacent said spring and coacting therewith, a detent restraining the member from movement in one direction, and an operating rotatable cam acting on said pivoted member and provided with a variable engaging face and an inoperative recess for applying pressure to the pivoted member upon one directional movement of the cam, and relieving the pressure upon the opposite directional movement of the cam, causing the pivoted member to enter the recess of the cam.

4. The combination of a spring, a pivoted member located adjacent to the spring and operative thereupon, and a cam having a disengaging face and a plurality of engaging faces of different radii positioned to bear upon and depress said pivoted member when rotated in one direction for applying pressure to the spring, said disengaging face of the cam adapted to rock said pivoted member out of operative position when the cam is rotated in the opposite direction for relieving the pressure on the spring.

5. In a wringer mechanism, the combination with opposing wringer rolls, one of which is mounted for movement toward and from the other, of a bowed spring mounted to react terminally upon said movably mounted

roll for effecting its resilient engagement with the other roll, a pivoted member located adjacent the spring and operative thereupon, a variable-faced cam positioned to act upon said pivoted member, and means for operating said cam for causing the pivoted member to exert pressure upon the spring when the cam is moved in one direction, and to impart a rocking movement to the pivoted member

10 for releasing the pressure on the spring when the cam is moved in another direction.

6. In a clothes wringer of the class described the combination with a pair of wringer rolls, one of which is movably mounted with respect to the other, of pressure applying means for said movable roll, including a bowed spring mounted to react terminally thereon, a pivoted member mounted intermediate of the spring and operative thereupon to exert pressure thereon, a laterally positioned detent in the path of movement of said member positioned to limit the motion of the pivoted member to pressure exerting position, and a cam having a plurality of individual operative faces adapted alternatively to be brought into

engagement with the pivoted member when the cam is rotated in one direction for applying pressure to the spring, said cam having a recessed portion for engaging the pivoted member when the cam is rotated in the opposite direction and allowing the pivoted member to be rocked for relieving the pressure on the spring.

7. The combination of a spring, a pivoted member mounted adjacent to the spring and operative thereupon, a laterally positioned detent therefor positioned to limit the pivotal motion of the pivoted member to position the same in pressure exerting position, a cam having a plurality of individual operative faces of varying radial position, for engaging the pivoted member and applying pressure to the spring when the cam is rotated in one direction, and means on the cam for causing the pivoted member to be moved for relieving the pressure on the spring when the cam is moved in the opposite direction.

In testimony whereof I do now affix my signature.

GEORGE L. HEDGES.
